INVENTOR.

William C. Davis,
By his Atty.

FIG. 2. *Henry Williams*.

UNITED STATES PATENT OFFICE.

WILLIAM C. DAVIS, OF LYNN, ASSIGNOR OF ONE-HALF TO EDWIN B. BALL,
OF NORTH READING, MASSACHUSETTS.

SHOE-JACK.

SPECIFICATION forming part of Letters Patent No. 386,867, dated July 31, 1888.

Application filed May 1, 1888. Serial No. 272,400. (No model.)

To all whom it may concern:

Be it known that I, WILLIAM C. DAVIS, of Lynn, in the county of Essex and State of Massachusetts, have invented new and useful 5 Improvements in Shoe-Jacks, of which the following is a specification.

In the accompanying drawings, in which similar letters of reference indicate like parts, Figure 1 is an elevation of a shoe-jack embodying my invention, with the last in position thereupon, certain portions of the holder being represented as broken out, the better to illustrate the invention. Fig. 2 is a vertical section on line *x*, Fig. 1.

15 *A* represents the base, which in practice is adapted to be screwed to the bench.

B is a round metallic box, whose bottom *B'* is secured to the base *A* by means of the bolt *C*, as shown, whereby said box is enabled to 20 be rotated on the stationary base. A rubber gasket, *D*, lies on the bottom *B'* and surrounds the bolt *C*, and a plate, *d*, centrally perforated to receive the bolt, lies upon the gasket. By means of the nut *d'* and check-nut *d''* the pressure of the plate upon the 25 gasket may be regulated, thus providing suitable friction, so that the box *B* may not be too easily rotated.

E is a plate or cover provided with the 30 hinge *E'*, whereby it is pivotally secured by means of the pin *e* to the box *B*, said box being provided with the ears *B''*, through which said pin extends. These ears are provided with steps *b*, which limit the motion of the 35 plate *E*, as, when said plate is tipped or swung over to its greatest extent, the wings *E''*, extending from the hinge *E'*, strike and rest upon said steps *b*. In order to provide friction whereby the plate may be held in any 40 desired position, a washer of soft metal, *e'*, is placed between the hinge *E'* and one of the ears *B''*, as shown.

H represents the holder, of substantially the shape shown, pivotally secured by means 45 of the bolt *I* to the plate *E*. A gasket, *J*, disk *K*, and nuts *K'* and *K''* are provided similar in construction and purpose to the gasket *D*, disk *d*, and nuts *d'* and *d''*. The gasket *J* is held in position by means of the

annular flange *E'''*, extending downward from 50 the plate *E*. The holder *H* is provided with a toe-piece, *H'*, which has grooves *h* formed in it in the ordinary manner for the adjustment and reception of the toe-support *L*, which is in this invention made so as to bend 55 or curve outward toward the toe of the last *S*, while the grooves which receive its lower end are substantially vertical. The heel-support *N*, which holds the heel of the last in the ordinary manner, is pivoted at *n* to the vertical 60 arms *O*, extending from the holder. A stiff spring, *P*, lies between the lower arm of the lever *N* and a partition, *H''*, in the holder, whereby the toe of the last is held firmly down upon the toe support *L*. 65

It will thus be seen that the jack may be adjusted to suit the operator, first, by rotating the box *B* upon the base *A*, by which it may be adapted for a right or left handed workman; second, by tipping the plate *E*, as shown 70 in broken lines in Fig. 2; and, third, by rotating the holder *H*, whether said plate be in its normal position or tipped.

All the parts of this device are preferably 75 constructed of metal.

Having thus fully described my invention, what I claim, and desire to secure by Letters Patent, is—

1. The herein-described improved shoe-jack, consisting, essentially, of the following parts, 80 viz: the stationary base *A*, box *B*, adapted to be rotated upon said base, plate *E*, pivotally secured to said box, whereby it may be swung up, as shown, and last-holder *H*, adapted to be rotated upon said plate, substantially as 85 and for the purpose set forth.

2. The combination of the base *A*, the bolt *C*, gasket *D*, disk *d* and nuts, the box *B*, provided with the ears *B''*, the bolt *I*, gasket *J*, disk *K* and nuts, the plate *E*, provided with the hinge *E'* and flange *E'''*, and the holder *H*, provided with the heel support *N* and toe-support *L*, substantially as and for the purpose described. 90

WILLIAM C. DAVIS.
